UNITED STATES PATENT OFFICE

152,660

DESIGN FOR AN ELECTRICAL HEATING AND
WELDING TRANSFORMERHarry B. Smith, Westfield, and George A. Dolan,
East Orange, N. J.

Application July 1, 1947, Serial No. 140,052

Term of patent 14 years

(Cl. D26—15)

To all whom it may concern:

Be it known that we, Harry B. Smith and George A. Dolan, citizens of the United States, residing at Westfield and East Orange (respectively), in the counties of Union and Essex, State of New Jersey, have invented a new, original, and ornamental Design for an Electrical Heating and Welding Transformer, of which the following is a specification, reference being had to the accompanying drawing, forming a part thereof.

In the drawing:

Figure 1 is a perspective view taken from one side and end of the electrical heating and welding transformer, showing our new design.

Figure 2 is a perspective view of the transformer, showing the opposite side and end.

We claim:

The ornamental design for an electrical heating and welding transformer, as shown.

HARRY B. SMITH.
GEORGE A. DOLAN.
